UNITED STATES PATENT OFFICE.

JAMES McINTOSH, OF GROVE CITY, PENNSYLVANIA.

GAS-ENGINE.

1,113,456.

Specification of Letters Patent. Patented Oct. 13, 1914.

Application filed July 27, 1910. Serial No. 574,098.

To all whom it may concern:

Be it known that I, JAMES McINTOSH, a citizen of the United States, residing at Grove City, in the county of Mercer and State of Pennsylvania, have invented new and useful Improvements in Gas-Engines, of which the following is a specification.

This invention relates to gas engines, and consists in certain improvements in the construction thereof as will be hereinafter fully described and pointed out in the claims.

The invention is specially useful in connection with two cycle engines.

One of the objects of my invention is to fill the transfer port or inlet passage with pure air so that when the connection is made between the pump chamber and the combustion chamber, there is this insulating column of air preventing back firing. This column of air is also useful in more thoroughly scavenging the combustion chamber, and the quantity of air admitted for this purpose is used in regulating the quality of the mixture, and thus the power of the engine.

Another object of the invention is to cool the piston, and to this end air is admitted to the piston. In addition thereto, the mixture, as it is transferred from the pump chamber to the combustion chamber, is forced past the inner end of the piston.

Other objects of the invention will appear from the specification and claims.

The invention is illustrated in the accompanying drawings as follows:

Figure 1 shows a center section of the engine with the piston at the end of its power stroke; Fig. 2 a similar section with the piston at the end of its compressed stroke.

1 marks the combustion end of the cylinder; 2 the piston; 3 the inlet port; 4 the exhaust port; 5 the water jacket. The front end of the cylinder is closed by a cylinder head 6, so that the pump chamber 7 is formed in the end of the cylinder. A piston rod 8 extends from the piston passing through the gland 9 which closes the head 6 around the piston rod, so as to prevent leakage from the pump chamber. The transfer port 10 is arranged in the cylinder, and extends from the inlet port 3 to a point in the pump chamber. A piston port 11 is arranged in the piston and opens within the piston 55 at the inner end of the piston, and has an

outer opening which, at the end of the power stroke, comes into register with the transfer port 10, as shown in Fig. 1.

12 marks the air inlet; 13 the gas inlet, the gas inlet being in annular form around the main air inlet and terminating in the jet openings 14 through the valve seat 15. A valve 16 controls the inlet, the air passing from the seat 15 picks up the gas, and forms the mixture. The valve is provided with the stem 17 which extends through the bearing 18. It is provided with a shoulder 19. A spring 20 is arranged around the stem between the bearing 18 and shoulder 19, and tends to hold the valve in a closed position. A port 21 extends around the cylinder, and opens into the pump chamber. The details of this inlet valve form no part of my present invention. During the compression stroke of the piston, a vacuum or partial vacuum is formed in the pump chamber, and the air pressure on the valve 16 opens the valve, and admits air and gas to the pump chamber. At the completion of the compression stroke the valve closes under the influence of a spring 20.

Arranged in connection with the transfer port is an air inlet 22. This is controlled by a valve 23. The valve has a stem 25 extending through a bearing 24, the bearing being supported by a web 26. A shoulder 27 is arranged on the outer end of the stem, and a spring 28 is arranged between this shoulder and the plate 30 resting on the web 26, the spring tending to hold the valve 23 in a closed position. The web 26 is provided with openings 29 and a plate 30 has openings 31 which may be brought into and out of register with the openings 29 by turning the plate. By this construction, the admission of air may be regulated simply by turning the plate so as to bring the openings 31 more nearly into or out of register with the openings 29. The valve 23 may also be adjusted by varying the spring pressure but I prefer the plate as it can be more conveniently adjusted.

The operation of the machine is as follows: Starting with the parts as shown in Fig. 1, the air which has been introduced into the piston port 11, the transfer port 10 and the mixture in the pump chamber are under the excess pressure due to the downward movement of the pump piston, so that

when the exhaust port 4 and inlet port 3 are uncovered, the air and mixture moves into the combustion chamber, the air preceding the mixture. It will be noted that the air in 5 the transfer port 10 and the piston port 11 insulates the burnt gases in the combustion chamber from the mixture so that there is little danger of the mixture being ignited from the burnt gases. At the same time it 10 will be noted that the mixture is all forced past and in contact with the inner end of the piston, thus cooling the piston and heating to the same extent the mixture. To facilitate this transfer of heat, I provide the 15 under side of the piston with the ribs or webs 2^a which not only have this effect, but strengthen the piston. As the piston moves upwardly the piston port 11 is brought opposite the inlet 3. By the time the piston 20 reaches this position, there has been such a reduction of pressure in the pump chamber that there is an immediate movement of gas from the transfer port 10, and the inlet port 3 to the piston port 11, and this is followed 25 by air through the passage 22, the valve 23 being opened by the air pressure on its outer surface. This is regulated so as to admit, at this point, any amount of air that is desired. Thus, not only the piston port 30 may be filled, but also the inner or upper end of the piston may be filled with pure air. On this upward or compression movement of the piston the mixture is also drawn in past the valve 16 in the usual manner. 35 In the latter part of the stroke of the piston, it uncovers the lower end of the transfer port 10, so that any mixture that may remain in this port is drawn out, and into the pump chamber, the transfer port being filled 40 with air from the passage 22.

In order to assure a pressure in the pump chamber approximately equal to atmospheric pressure, when the piston starts its return movement, I prefer to provide the 45 air port 32 leading to the air inlet 12. An auxiliary piston port 33 is arranged in the piston, and in position to be brought into register with the port 32, when the piston is in its extreme initial position. If the 50 pressure in the pump chamber is, at this point, less than atmospheric pressure, air passes in through the air inlet 12, by way of port 32 and 33, to the inner end of the piston, augmenting the air brought in 55 through the piston port 11. It is desirable to place this auxiliary piston port over the exhaust port, so that the air drawn in along this port close to that part of the piston which is brought into contact with the 60 highly heated parts of the cylinder next the exhaust port, is cooled thereby. On the power stroke of the piston, the gases and air retain approximately their position until the piston port 11 is brought into register 65 with the transfer port 10 as shown in Fig.

1, when a charge is delivered to the combustion chamber.

What I claim as new is:

1. In a gas engine, the combination of a cylinder; an inlet passage through which mixture is delivered to the cylinder; a pump connected with said passage; means closing said passage to the pump during part of the suction stroke of the pump; a pressure actuated valve for admitting air to the passage in position to precede a charge of mixture; and an intake independent of said valve for the pump. 70

2. In a gas engine, the combination of a cylinder; an inlet passage through which mixture is delivered to the cylinder; a pump connected with said passage; means closing said passage to the pump during part of the suction stroke of the pump; a valve for admitting air to the passage in position to precede a charge of mixture; means for varying the quantity of air admitted; and an independent intake for the pump. 80

3. In a gas engine, the combination of a cylinder; a piston in the cylinder forming with one end of the cylinder a pump; an inlet passage forming a transfer port from the pump end of the cylinder to the combustion end of the cylinder, said piston and transfer port being arranged to close the transfer port during part of the suction stroke of the piston; a valve for admitting air to the passage near the combustion end of the cylinder; and an independent intake for the pump. 90 95

4. In a gas engine, the combination of a cylinder; a piston in the cylinder; a transfer port; an air valve in the transfer port; a port in the end of the piston adapted to be brought into connection with the transfer port to receive air from the transfer port; and a separate intake for delivering mixture to the pump cylinder. 100 110

5. In a gas engine, the combination of a cylinder; a piston in the cylinder; an inlet passage forming a transfer port from the pump end of the cylinder to the combustion end of the cylinder; an air inlet valve on the 115 said inlet passage; a port in the piston receiving air from said inlet passage, the said port being open to the piston and placed to be brought into register with the transfer port at the end of the power stroke 120 of the piston whereby mixture is forced from the piston to the transfer port; an independent intake for delivering mixture to the pump end of the cylinder; and an inlet for air open at the end of the suction stroke 125 of the piston for relieving the vacuum in the pump end of the cylinder.

6. In a gas engine, the combination of a cylinder; a piston in the cylinder; an inlet passage forming a transfer port from the 130

pump end of the cylinder to the combustion end of the cylinder; an air inlet valve on the said inlet passage; a port in the piston receiving air from said inlet passage, the 5 said port being open to the piston and placed to be brought into register with the transfer port at the end of the power stroke of the piston whereby mixture is forced from the piston to the transfer port; an independent intake for delivering mixture to the pump end of the cylinder; and an auxiliary inlet for air, said auxiliary inlet for air leading to the end of the piston for delivering air from the pump end to the extreme 10 end of the suction stroke to relieve the vacuum therein and to deliver the air adjacent to the discharge port in the piston at the end of the compression.

7. In a gas engine, the combination of a cylinder; a piston in the cylinder; an inlet passage forming a transfer port from the pump end of the cylinder to the combustion end of the cylinder; an air inlet valve on the said inlet passage; a port in the piston receiving air from said inlet passage, the said port being open to the piston and placed to be brought into register with the transfer port at the end of the power stroke of the piston whereby mixture is forced from the 25 piston to the transfer port; and a port in the cylinder and piston open at the end of the suction stroke to convey air to the end of the piston to relieve the vacuum in the pump end of the cylinder at the end of the 30 suction stroke and to place the air so delivered in a position to be initially dis-

charged from the discharge port in the piston.

8. In a gas engine, the combination of a cylinder; a piston in the cylinder forming with the cylinder a pump plunger; an inlet passage through which mixture is delivered to the cylinder; devices for delivering a column of air to the inlet passage, and from the inlet passage to the piston; an auxiliary device for delivering air to the inner end of the piston at the extreme end of the stroke of the piston, said passages and piston being arranged to compel a movement of the air in advance of the mixture through the inlet passage to the combustion end of the cylinder.

9. In a gas engine, the combination of a cylinder; having an inlet port 3; a transfer passage 10; an auxiliary air port 32; an air inlet valve on the transfer passage; a piston in the cylinder having a piston port adapted to be brought into register with the inlet port to the transfer passage, and leading from the inner end of the piston, and having the auxiliary port 33 adapted to come into register at the extreme compression of the piston with the auxiliary port 32, the port 33 leading to the inner end of the piston.

In testimony whereof I have hereunto set my hand in the presence of two subscribing witnesses.
